SOAP DISH

Frank Yercheck, 17916 Crenshaw Blvd., Torrance, Calif.

Filed Aug. 31, 1964, Ser. No. 81,530

Term of patent 14 years

(Cl. D4—3)

The bottom is substantially plain.

I claim:

The ornamental design for a soap dish, as shown and described.
